UNITED STATES PATENT OFFICE.

JOHN JOSEPH BERRIGAN, OF ORANGE, NEW JERSEY, ASSIGNOR TO FRANCIS J. AREND, OF NEW YORK, N. Y., AND JOHN BERNSTROM, OF STOCKHOLM, SWEDEN.

CENTRIFUGAL MACHINE.

SPECIFICATION forming part of Letters Patent No. 737,063, dated August 25, 1903.

Application filed November 26, 1902. Serial No. 132,875. (No model.)

To all whom it may concern:

Be it known that I, JOHN JOSEPH BERRIGAN, of Orange, Essex county, New Jersey, have invented a new and useful Improvement in Centrifugal Machines, of which the following is a specification.

The invention relates to a centrifugal apparatus for the separation of solids and liquids, and more particularly to the type of such apparatus disclosed in United States Letters Patent No. 677,926, granted to me July 9, 1901.

My present invention consists in a machine in which two separations of the combined materials successively occur, the first separation delivering the solid material, with some small residue of moisture, and the second separation operating to remove this residue; also, in the construction whereby the dry surface over which the deposited solid material is carried in contact with the atmosphere is largely augmented; also, in the construction of the apparatus whereby one separating-receptacle is inclosed in the other separating-receptacle; also, in the construction whereby the initially-separated material is delivered to a centrifugal strainer or filter, whereby it is again separated as aforesaid; also, in the combinations and instrumentalities more especially pointed out in the claims.

In the accompanying drawings, Figure 1 is a diametral transverse section of the operating parts of my device. Fig. 2 is a detail of the gearing in section on the line 2 2 of Fig. 1. Fig. 3 is a horizontal section on the line 3 3 of Fig. 1.

Similar letters and numbers of reference indicate like parts.

The outer receptacle A is composed of the circular bottom plate 4 and the inverted cup 5. The lower edge of cup 5 is flanged, and the circumference of the bottom plate 4 is threaded to receive a threaded ring 6, the upper flange 7 of which extends over the cup-flange. By means of ring 6 cup and bottom plate are tightly drawn together and the joint is packed by a gasket 8 between them.

The receptacle A is centrally supported upon the hollow shaft B. This shaft is in turn supported upon any suitable standard and rotated by mechanism, all substantially as

shown in Letters Patent No. 677,926, granted to me as aforesaid, in connection with the hollow shaft 6 of the apparatus therein disclosed.

Within the receptacle A and with its edge received in a recess in the bottom plate 4 is an inverted cup 9, the circular wall 10 of which is perforated and forms a partition in said receptacle. Between an opening 11 in cup 9 and a smaller opening 12 in the inverted cup of receptacle A there is a tapered passage or channel 13. In the radial partitions 33, above and below said channel, are openings 14, Fig. 1, to allow free flow of liquid around receptacle A.

Supported from the under side of the top of cup 9 is a second receptacle C. This is formed of the cup portion 15 and the annular inner partition 16, eccentrically disposed in said cup. In the partition is an opening 17, which communicates with a smaller opening 18 in cup 15 by a passage 19. In the radial partitions 20, above and below this passage, are openings to allow free flow of liquid in the crescent-shaped space H between cup 15 and lining 16.

Disposed centrally within the receptacle A and in the top of cup 9 is the feed-inlet pipe 22, below which and on the inner side of the top of cup 15 is supported the feed-receiving compartment 23. Said compartment is open on one side 24.

Within the hollow shaft B is a shaft D, which enters the receptacle A and carries the scrapers E, the vertical edges of which are in proximity to the perforated wall 10. On the lower side of receptacle C is a box 25, in which is stepped the vertical shaft 26. Said shaft 26 carries an annular pinion 27, having interior teeth which engage with the pinion 28 on shaft D, as shown in Fig. 2. Shaft 26 extends through receptacle C and into the feed-compartment 23. In receptacle C it has an enlarged hub 29, from which extends the arms 30, carrying scrapers F, the vertical edges of which are in proximity to the inner partition 16 of receptacle C. In the feed-compartment 23 shaft 26 carries scrapers G, the vertical edges of which are in proximity to the wall of said compartment.

The crescent-shaped space H between the cup portion 15 and inner wall 16 of receptacle C communicates with the space I between per-

forated wall 10 and cup 5 of receptacle A by means of a pipe 31. In the bottom plate 4, between said wall 10 and cup 5, is an outlet-pipe 32.

- 5 The shafts B and D being set in rotation, the operation of the apparatus is as follows: The combined solid and liquid material to be separated enters by the inlet-pipe 22 to the feed-receiving compartment 23. Thence by 10 the action of the centrifugal force and the scrapers G it is projected outward and upon the portion of the inner wall 16 of receptacle C which is most eccentric with respect to the rotation axis of shaft B. The liquid escapes 15 by the short tubes 34 in the inner partition 16 to the space H between said partition and cup 15 and thence by the pipe 31 to the space I, and so to outlet-pipe 32. The solid ingredient as fast as projected against the inner wall 16 20 of receptacle C is carried by the scrapers F from its place of deposit to and over the substantially dry portion of the surface of said wall (the formation of which is fully explained in my aforesaid Letters Patent) and 25 to the passage 19, whence by the action of the centrifugal force of rotation it is projected against the inner surface of the perforated wall 10. This wall is here shown as concentric with the axis of rotation of receptacle A. 30 As fast as the solid material is thrown upon the portion of the wall 10, directly opposite the passage 19, it is removed by the scrapers E and carried around the inner surface of said wall to the outlet-passage 13, whence, as 35 before, by the centrifugal force of rotation it is finally ejected. Such moisture as may remain in the solid material after reaching perforated wall 10 is strained through its perforations and escapes to the liquid-outlet pipe 32. 40 From the foregoing it will be seen that the combined material under treatment is practically twice separated, first in the receptacle C and then in the receptacle A. In the receptacle C it undergoes substantially the same 45 separation as takes place in the machine described in my aforesaid Letters Patent. Then instead of escaping at once from the apparatus it is subjected to a second treatment, whereby whatever moisture remains in 50 it is ejected by centrifugal force through the perforations in wall 10 before said material is finally delivered. As already fully explained in my aforesaid Letters Patent, the solid material in receptacle C is carried by 55 the scrapers over a substantially dry space on the inner wall of said receptacle before it reaches the outlet-passage 19, and is thus dried by the atmosphere. Inasmuch as the action of the centrifugal force of rotation is 60 to cause the liquid passing by pipe 31 and the perforations in wall 10 to the space I, between wall 10 and cup 5, to form a ring against the inner surface of said wall, which ring does not extend inwardly beyond the 65 outlet-pipe 32, it follows that the inner surface of wall 10 is also dry, so that thus an additional and much more extensive dry space

is provided over which the solid material is transported before it reaches the final escape-passage 13. Therefore not only is the 70 combined material subjected to two separations but the solid ingredient is carried over a greatly augmented dry area, and thus submitted for a longer period to the evaporating action of the atmosphere, so that from the 75 finally-ejected solid a greater proportion of moisture is removed than is accomplished when the foregoing construction is not present.

I claim—

1. In a centrifugal machine, a rotary shaft, 80 a separating device carried and rotated by said shaft, and a second separating device supported within and upon said first device, the said device being provided with openings whereby the combined materials are introduced into the inner device and after separation one of said materials is conducted to said outer device, substantially as described.

2. In an apparatus for the separation of solids and liquids, a rotary receptacle and 90 within the same a strainer constructed to receive the materials to be separated; the said receptacle having an outlet at a distance from said strainer and between said strainer and the circumferential wall of said receptacle, substantially as described.

3. In an apparatus for the separation of solids and liquids, a rotary receptacle and a cylindrical chamber therein having a perforated wall; the said receptacle having an 100 opening in its bottom communicating with the space surrounding said chamber, and at a distance from said perforated wall, substantially as described.

4. In an apparatus for the separation of 105 solids and liquids, a rotary receptacle and a chamber therein concentric therewith and having a perforated wall; the said receptacle having an opening in its bottom communicating with the space surrounding said chamber and at a distance from said perforated wall, substantially as described.

5. In an apparatus for the separation of 115 solids and liquids, a rotary receptacle, a perforated annular partition within the same and means for delivering the materials to be separated into the space inclosed by said partition; the said receptacle having an outlet between said partition and the inner circumferential surface of said receptacle, substantially 120 as described.

6. In an apparatus for the separation of 125 solids and liquids, a rotary cylindrical receptacle having an opening in its circumferential wall and an opening in its bottom, partitions 130 between said openings, an annular perforated partition within said receptacle and means for delivering the materials to be separated into the space inclosed by said annular partition; the said outlet in the bottom of said 135 receptacle being disposed between the inner circumferential surface of said receptacle and said perforated partition, substantially as described,

7. In an apparatus for the separation of solids and liquids, a rotary receptacle, an annular perforated partition within the same and means within said receptacle for centrifugally projecting the materials to be separated against the inner surface of said partition; the said receptacle having an outlet between said partition and the inner circumferential surface of said receptacle, substantially as described.

8. In an apparatus for the separation of solids and liquids, a rotary receptacle, an annular perforated partition within the same, a conduit between openings respectively in said partition and said receptacle, means for delivering the material to be separated into the space inclosed by said partition, and means for conveying the solid material deposited on said partition to said conduit, substantially as described.

9. In an apparatus for the separation of solids and liquids, a rotary receptacle, an annular perforated partition within the same, a conduit between openings respectively in said partition and said receptacle, means for delivering the material to be separated into the space inclosed by said partition, and means for conveying the solid material deposited on said partition to said conduit; the said receptacle having an outlet between said partition

and the inner circumferential surface of said receptacle, substantially as described.

10. In a centrifugal machine, the combination of the rotary receptacle A, having openings 12 and 32, the circular perforated partition 10 within said receptacle having opening 11, the said openings 11 and 12 being connected by a passage 13, revolving scrapers E within said partition, and means for delivering into the space inclosed by said partition the combined materials to be separated, substantially as described.

11. In a centrifugal machine, the combination of the rotary receptacle A having openings 12 and 32, the circular perforated partition 10 within said receptacle having opening 11, the said openings 11 and 12 being connected by a passage 13, revolving scrapers E within said partition, the receptacle C having openings 17 and 18, passage 19 connecting said openings and within said receptacle the revolving scrapers F, substantially as described.

In testimony whereof I have signed my name to this specification in the presence of two subscribing witnesses.

JOHN JOSEPH BERRIGAN.
